(57) **CLAIM**

The ornamental design for a tracker bearing support, substantially as shown and described.

DESCRIPTION

FIG. 1 is a top left perspective view of a tracker bearing support showing the claimed design;

FIG. 2 is a top right perspective view thereof;

FIG. 3 is a front view thereof;

FIG. 4 is a rear view thereof;

FIG. 5 is a top view thereof;

FIG. 6 is a bottom view thereof;

FIG. 7 is a left view thereof; and,

FIG. 8 is a right view thereof.

Portions of the tracker bearing support that are not shown form no part of the claimed design.

The dashed lines in the figures show portions of the tracker bearing support that form no part of the claimed design.
